UNITED STATES PATENT OFFICE.

MORRIS G. ROSENTHAL, OF CLEVELAND, OHIO, ASSIGNOR TO THE CLEVELAND CRANE AND ENGINEERING COMPANY, OF WICKLIFFE, OHIO, A CORPORATION OF OHIO.

TEXTILE-TREATING CARRIER.

Application filed March 30, 1927. Serial No. 179,503.

This invention relates to textile treating carriers for use in subjecting textile materials to chemical treatment by dipping in a suitable chemical solution, for washing such 5 materials or for drying the same.

The present invention has for its object to provide means by which such treating, washing or drying operations may be performed more rapidly or more effectively and 10 by which the action on the textile material is more uniform.

One important application of the present invention is to the treatment of artificial silk fiber which after being spun and wound in 15 spools is subjected to a treatment in an acid solution. The present invention provides means by which the fibers throughout the spool are caused to be uniformly acted upon by the solution and by which the time the 20 spools are required to remain in the solution may be greatly reduced.

With the above and other objects in view, the invention may be said to comprise the 25 device as illustrated in the accompanying drawings hereinafter described and particularly set forth in the appended claims together with such variations and modifications thereof as will be apparent to one skilled in the art to which the invention appertains.

Reference should be had to the accompanying drawings forming a part of this 30 specification in which:

Fig. 1 is a sectional elevation showing the carrier lowered into a dipping tank and the spool supporting frame connected to a suction pump on the tank for circulating the liquid through the spools and hollow supporting frame.

Fig. 2 is an end elevation of the carrier. 40 Fig. 3 is a section taken on the line indicated at 3-3 in Fig. 2.

As illustrated herein the carrier of the present invention is adapted to travel along an overhead trackway indicated by the numeral 1 for conveying the textile material to and from the dipping tank. In Fig. 1 of the drawing the carriers are shown in lowered position with the spool supporting frame positioned in a dipping tank 2, the lowering of the carrier being accomplished by means of a drop track section 3 which is adapted to be lowered from a position in alignment with the main track 1 to a position directly over the dipping tank. The

carrier includes a carriage 4 adapted to travel along the track 1 and suspended from this carriage by means of suitable flexibly connected hangers 5 is a spool supporting frame 6 which is formed of pipes. The frame 6 is rectangular in form and has end 60 members 7 formed of short sections of tubing and tubular cross members 8 extending between the end members 7. The upper and lower cross members are connected to the end members by suitable fluid-tight elbow 65 fittings 9. The intermediate cross members are connected to the end members by suitable fluid-tight T-fittings 10. Intermediate the ends thereof the tubular cross members are provided at intervals with diametrically 70 opposite openings 11 and secured to the tubular members over the openings are fittings 12 which have enlarged lateral extensions 13. These extensions are provided with central threaded openings 14 which receive the inner 75 threaded ends of rods 15 which extend outwardly from the cross members at right angles thereto. The extensions 13 also have openings 16 surrounding the central threaded openings 14 so that a passage is provided 80 through the fittings to the interior of the tubular member. The extensions 13 are provided with shoulders 17 adapted to support the inner ends of cylinders 18 which are provided with circumferentially spaced elongated openings 19. The cylinders 18 form supports for spools 20 of textile material, each cylinder being adapted to support two spools end to end and having two sets of longitudinally spaced openings 19, one with 85 in each of the spools supported thereon. The openings 19 extend throughout the major portion of the periphery of the cylinder and each spool 20 is of substantially the same length as the openings, the spools being positioned on the cylinder over the openings by means of spacers 21 at the inner end of the cylinder, intermediate spacers 22 and 22' and spacers 23 at the outer ends of the cylinders which are engaged by clamping disks 24 provided with central openings to receive the rods 15 and clamped against the end of the cylinder by means of nuts 25 on the outer threaded ends of the rods 15.

One of the corner fittings of the frame 6 is provided with an extension 26 adapted to be coupled by any suitable disconnectable coupling means to a pipe or hose 27 extend-

ing to the inlet of a suction pump 28 which has a discharge pipe 29 extending into the upper portion of the tank.

The spool supporting rack is filled with 5 spools of textile material from the spinning machine and is then moved along the track-way to the drop track section 3 over the dipping tank whereupon the tank section is lowered to submerge the spools in the liquid 10 in the tank. The extension 26 of the frame is then connected to the suction pump 28 which creates a reduction of pressure within the hollow frame causing liquid to be drawn through the spools into the cylinders 18 and 15 from the cylinders 18 through the frame to the suction pump. The passage of liquid through the spools causes the material in the spools to be quickly and uniformly saturated with the solution so that the length of time 20 required for the treatment of the material is greatly reduced. After the treatment of the spools in a tank containing a suitable chemical solution the spools may be washed in a similar tank containing pure water and the 25 washing operation is also greatly facilitated by the suction through the supporting frame. If desired, the suction may be employed to hasten the drying of the spools by drawing air through the spools and hollow frame by 30 means of a suction pump.

Having thus described my invention, what I claim is:

1. A textile treating carrier comprising a frame having end and cross members formed 35 of tubing connected by fluid-tight joints and having means adjacent the top thereof for connecting the same with a suction pump, and hollow perforated spool receiving cylinders attached to fittings secured to the cross 40 members and supported exclusively thereby, said cylinders and tubular cross members being in communication through said fittings.

2. A textile treating carrier comprising a carriage adapted to travel along an overhead 45 trackway, a hollow frame arranged in a vertical plane and suspended from the car-

riage, said frame having means whereby it may be connected to a pump, and hollow perforated spool receiving cylinders attached to and supported exclusively by said 50 frame and communicating with the interior thereof, whereby liquid may be circulated through the material in the spools on the cylinders.

3. A textile treating carrier, comprising a 55 frame made up of spaced horizontally arranged tubes and vertical end tubes connected to all of said horizontal tubes by fluid tight joints, a fluid pump, means permitting the connection and disconnection of said 60 pump and frame, and perforated spool supports mounted exclusively upon said horizontal tubes, projecting laterally therefrom and connected with the interior thereof by 65 openings in said tubes.

4. A textile treating carrier, comprising a vertical frame including a plurality of parallel tubes interconnected at their ends, a fluid pump, means permitting the connection and disconnection of said pump and 70 frame, and perforated spool supports mounted exclusively upon said tubes, projecting laterally therefrom and connected with the interior thereof by 75 openings in the tubes.

5. A textile treating carrier, comprising a vertical frame including a plurality of parallel tubes, means at the respective ends 80 of said tubes for connecting them rigidly together and preventing the escape of fluid, said means at one end providing fluid interconnections for all of said parallel tubes, a fluid pump, means permitting the connection and disconnection of said pump from the last named end of said frame, and perforated 85 spool supports mounted exclusively upon said tubes, projecting laterally therefrom and connected with the interior thereof by openings in the tubes.

In testimony whereof, I hereunto affix my signature.

MORRIS G. ROSENTHAL.
